FIG. 1 is a side, top perspective view of a first embodiment of a bottle showing my new design;

FIG. 2 is a side elevational view thereof, all remaining sides being mirror images thereof;

FIG. 3 is a top plan view thereof;

FIG. 4 is a bottom plan view thereof;

FIG. 5 is a side, top perspective view of a second embodiment of a bottle showing my new design;

FIG. 6 is a side elevational view thereof, all remaining sides being mirror images thereof;

FIG. 7 is a top plan view thereof;

FIG. 8 is a bottom plan view thereof;

FIG. 9 is a side, top perspective view of a third embodiment of a bottle showing my new design;

FIG. 10 is a side elevational view thereof, all remaining sides being mirror images thereof;

FIG. 11 is a top plan view thereof; and,

FIG. 12 is a bottom plan view thereof.

The broken lines in the figures represent portions of the article which form no part of the claimed design.
